FOLDABLE PACKAGE CARRIER

Leon Fleck, Bronx, and Gabriel Suchestow,
New York, N. Y.

Application January 9, 1941, Serial No. 373,744

3 Claims. (Cl. 280—41)

This invention relates to package and article carriers of the foldable type, and more particularly to a carrier which is adapted to be moved along on wheels over the ground.

In accordance with the invention we have provided a package carrier which includes two sticks one of which is provided with a curved handle. The two sticks have a common pivot near their upper ends which is provided with one or more hooks for suspending articles or packages therefrom. The lower ends of the two sticks are provided with wheels for moving the device over the ground. Each of the two sticks has a strut near its lower end, the free ends of the two struts being connected together by a pin. The struts serve to space the lower ends of the wheel carrying sticks and are adapted to be folded together. Means are provided for preventing the two struts from moving downwards out of a horizontal line. Thus a substantially isosceles triangle is formed when the two struts are substantially horizontal.

In order to fold the package carrier of the invention the two struts are moved upwardly on their pivot and the two sticks forming the carrier frame are locked together by means of a suitable catch. When the carrier is unfolded, the two wheels are substantially arranged one behind the other and are slightly offset. The one stick that is provided with the curved handle is adapted to turn about its axis through 360°. Hence, it will be seen that the package carrier can be steered easily by means of the handle on one of the sticks.

It is accordingly an object of the invention to provide an improved package carrier that moves on wheels and can be easily carried about in its folded state.

Another object of the invention is to provide a package carrier that can be steered by rotating its front wheel secured to a stick having a curved handle for the manipulation thereof.

Still an object of the invention is to provide a carrier of the type disclosed which has an upper pivot point provided with at least one hook for carrying packages thereon.

A further object of the invention is to provide a locking means for locking the carrier in its folded state.

These and further objects of the invention will become more evident in the following description of a preferred embodiment of the invention illustrated in the drawing, wherein:

Fig. 1 is a side view of the package carrier of the invention.

Fig. 2 is a front view of the carrier of Fig. 1.

Fig. 3 is a side view of the device of Fig. 1 showing our improved package carrier in its folded state.

Fig. 4 is a section on enlarged scale along the line 4—4 of Fig. 3 showing the two struts in folded position and their T-shaped locking member.

Fig. 5 is a section on enlarged scale along the line 5—5 of Fig. 3 illustrating the interlocking mechanism for locking the two sticks or rods 10 when the carrier is folded.

Fig. 6 is a section on the line 6—6 of Fig. 5.

Fig. 7 is a side view of the two connecting struts on enlarged scale illustrating the T-shaped locking member that prevents collapsing of the struts.

Fig. 8 is a view in perspective showing the T-shaped locking member of Fig. 7.

Referring more particularly to the drawing the package carrier of the invention comprises a stick or rod 10 having a curved handle 11 for manipulating the carrier. Hence, members 10, 11 have the shape of a walking stick. The carrier includes a second stick or rod 12 which is shorter than stick 10. Stick 10 and rod 12 are pivoted at

25 13. Stick 10 is provided with sleeve 14 which is integral with shaft 15 projecting through rod 12. Sleeve 14 is freely rotatable about stick 10 and its longitudinal displacement with regard to stick 10 is prevented by rings 16, 16 secured to stick 10.

30 Thus it will be seen that stick 10 can freely turn about its axis through an angle of 360°. Suspending member 17 having two hooks 18, 18 is rotatably mounted on shaft 15 between stick 10 and rod 12. The lower end of rod 12 is secured to sleeve 19 having a bifurcated extension 20. Wheel 21 which preferably has a rubber tire 22 is rotatably mounted in the two forks of extension 20. The lower end of stick 10 is rigidly secured to sleeve 23 having a bifurcated extension 24 of substantially the same shape as extension 20. Wheel 24 having a rubber tire 25 is rotatably mounted within extension 24.

35 40 45 A strut member 26 is pivoted at 27 on a projecting portion 28 of sleeve 19. Ring 30 is rotatably mounted on sleeve 23 and has a projecting portion 31. Collar 39 is secured to stick 10 above ring 30 to prevent movement thereof longitudinally of stick 10. Pin 32 is rotatably mounted on projection 31. Strut member 33 is mounted

50 55 on pin 32 to oscillate thereon.

The manner of connecting struts 26 and 33 to provide for a foldable carrier is shown more particularly in Figs. 7 and 8. The free ends of struts 26 and 33 are rotatable about pivot 34 which supports a T-shaped locking member 35. Locking

member 35 has a horizontal plate 36 which extends across the upper surfaces of struts 26 and 33. As will be readily seen the T-shaped locking member 35 will prevent a further collapse of struts 26 and 33 from their position of Fig. 1. On the other hand, by gripping plate 36 of locking member 35 the two struts 26 and 33 can be swung upwardly.

The means for interlocking the two sticks 10 and 12 when the carrier is in its folded position is shown more particularly in Figs. 5 and 6. For this purpose a portion of sleeve 23 is cut out and shaped to form a hinge 40. Hinge 40 supports pin 41. U-shaped locking member or stirrup 42 is secured to pin 41. Sleeve 19 of rod 12 is provided with a cut-out hook-shaped portion 43 which is adapted to interlock with stirrup 42.

The operation of our improved package carrier will now be evident. In its unfolded state, shown in Figs. 1 and 2, the carrier can be pulled along over the ground and can be steered by rotating handle 11. T-shaped locking member 35 prevents the further collapse of struts 26 and 33. Packages and articles to be carried can be suspended from hooks 18, 18. The carrier will be pushed in front of the operator so that the person using our improved package carrier will always be able to see the packages or articles suspended from hooks 18, 18.

When the carrier is not used for carrying packages or articles, it is folded as shown in Fig. 3. At first, plate 36 of locking member 35 is gripped and lifted until the struts 26 and 33 assume the position of Fig. 3. Now stirrup 42 is engaged with hook 43 to lock the carrier. By locking sleeves 20 and 23 any displacement of pivots 27 and 32 is prevented. In its folded state our improved package carrier can be easily carried about and takes up a minimum of space.

It will be appreciated that, when the carrier is in its unfolded state, the two wheels 21, 24 are substantially arranged one behind the other, although the wheels are slightly offset, as may be observed from Fig. 2. It is possible to arrange rod 12 in the position of Fig. 2, or else rod 12 may be arranged on the right hand side of stick 10. When the package carrier is mounted as shown in Figs. 1 and 2, wheel 24 will be arranged to the right of wheel 21. This embodiment of the invention is particularly adapted to be operated by the right hand of the person. When wheel 24 is arranged to the left of wheel 21, the carrier is particularly adapted to be steered by the left hand of the operator. Thus our improved package carrier can be adapted for use for right handed and left handed persons.

Various changes and modifications may be made to the details of construction of the inven-

tion without departing from the broader spirit and scope thereof, as set forth in the following claims.

We claim:

1. A package carrier comprising a rod and a stick formed with a curved handle at its upper end, a sleeve freely rotatable about said stick, means for preventing longitudinal displacement of said sleeve in said stick, a shaft rotatably connected with said sleeve and piercing said rod to provide a common pivot for said stick and said rod, a suspending member having at least one hook being secured to said shaft for suspending packages therefrom, a wheel rotatably mounted at the lower end of said stick, a strut rotatably mounted on said rod near its lower end, a ring rotatable on said stick and having pivoted thereon a second strut the free ends of said struts being pivoted to each other by a pin, a T-shaped locking member on said pin for preventing collapse of said struts, and a catch on said stick for disengageably securing said stick and said rod in a position where they are in one plane, whereby the carrier can be folded and unfolded by swinging said struts upwards and downwards on said common pivot.

2. A package carrier including a rod and a stick formed with a handle at its upper end, a wheel rotatably mounted at the lower end of each of said stick and said rod, a sleeve freely rotatable on the upper portion of said stick and secured against longitudinal displacement, said rod and said stick being rotatable about a shaft piercing said rod, said shaft being rotatable on said sleeve, a suspending member on said shaft, means for holding the lower ends of said stick and said rod in a predetermined distance, a hinge journaling a horizontal shaft therein, said hinge being struck out from the lower end of said stick, a hook-shaped member being struck out from said rod opposite said hinge, an oscillatable stirrup on said horizontal shaft for engagement with said hook-shaped member to lock said carrier in its folded position.

3. In a package carrier having a substantially straight rod and a substantially straight stick, a sleeve freely rotatable about said stick, means for preventing movement of said sleeve longitudinally of said stick, a shaft extending from said sleeve substantially at right angles with respect to said stick and projecting through said rod, said shaft being rotatable about said stick, whereby said stick is rotatable about its longitudinal axis and said stick and said rod are rotatable about an axis passing through both said stick and said rod.
